(54) **WASHING MACHINE, & SCOURING, &C.**

(76) Inventor: **Camm Moore**

James Moore of the County of Guilford. N. Carolina.

Letters Patent.

The schedule referred to in these Letters Patent and a copy part of the same containing a description in the words of the said James Moore himself of his improvement in the setting, washing, machine for washing clothes, wool, and scouring leather,

To all to whom these presents shall come,
Be it known that I, James Moore of the County of Guilford & State of North Carolina, have invented a new and useful improvement in a machine for washing clothes, wool & scouring leather with various other domestic purposes, and that the following is a full and exact description of the construction & operation of the said machine as invented by me.

These machines are made with 2 or 3 rollers as the case may require the small machine for family washing, are made with 2 heads to each roller as follows, take two boards, or plank crofs and nail them together (where good firm plank 3 inches thick can be had they may be made of one piece) round them to 13 $\frac{1}{2}$ inches diameter; make a central mortice 2 inches square, to receive an angle of heavy board 16 inches square shouldered 4 1/2 inches the whole length.

Take a strip of paper, measure round one head of the roller, lay the paper off into 25 steps with the compasses, then put the paper round the head of the roller, and mark through the steps for laying on the slats.

Let the slats be made 2 inches wide 1 $\frac{1}{2}$ inch thick and warped down to 1 $\frac{1}{2}$ inch face, 8 $\frac{1}{2}$ inch for the inner edge, 16 inches long shouldered at each end $\frac{1}{2}$ inch to nail on the heads, where they were laid off or marked, they must be bored or countersunk then nailed on the heads in a bias from one roller being bias to the right the other to the left to prevent their breaking by putting on the slats bias, the ends are higher than the middle they must be taken off with a jointer to bring them level.

Cutting steps off the ends of the slats and setting the small ends

little rounding, to prevent chafing the clothes. There must be a $\frac{1}{2}$ inch hole bored in the center in each end of the axles to receive an iron grub gear $\frac{1}{2}$ inches long made in the form of a spike $\frac{1}{2}$ but one inch, this made round and smooth to receive the coupling rods which are two rods of iron exactly of a length with a hole in each end and long enough to allow the rollers to run entirely free of each other. They must be bored out in the middle to prevent their coming off, or scotching the heads of the setting. If handles are used instead of the screw they are made like plough handles, only less thinner and lighter with a round to hold them in place. & on the inside of the lower end, a flat piece of iron $\frac{1}{2}$ inches long put on with screws with a hole at the lower end, to go on the grub gear over the coupling rods.

The rollers are done which are the first things to be made and the back part, to be made to receive the rollers without rubbing.

The boards or plank should all be good timber (pine) and without sap & when dressed out of the dimension, specified. Where a wooden bottom is intended, the water bed is first to be made, this side plank must be one inch thick and $\frac{1}{2}$ inches wide and long enough to allow the straight parts of the bottom to be 14 feet 8 inches long. The ends of the side plank are slanted out boat fashion to an angle of about 165 degrees the short end edge down. The bottom and ends of good inch blank put across making the water bed a box wide enough, to allow the rollers $\frac{1}{2}$ inch play between the sides of the water bed. The bottom must be nailed with 8d. nails in a zigzag form to prevent splitting the plank. Drop off the ends of the bottom even with the side plank, & put on a neat and well fitted moulding on each side, nailing it to the ends of the bottom & to the side plank, then a border plank $\frac{3}{4}$ inch thick & $\frac{1}{2}$ inches wide, is to be put on the outside of the water bed with $2\frac{1}{2}$ inches lap, the ends square with a similar plank. 14-iron clamps at each end and one at each corner, upon the border and also on the water bed, then put a short moulding over the clamps.

The light frame to support the counter bottom is made of two pieces of good strong wood 1 inch thick $\frac{1}{2}$ inch wide & as long as the inside of the principal bottom. There must be a round notch in the middle of the upper 1 inch wide $\frac{1}{2}$ inch deep, after the 3 feet and 8 inches, from the

from the notch they must be started to each end leaving the ends not more than $\frac{1}{2}$ inch thick to make each side of the notch in both must be a small mortise to allow 2 pieces of elastic wood with a tenon at each end long enough to go this to the sides and have the long notched pieces 2 inches from the sides and the tenons fastened in with 16 nails.

The counter bottom is made of lath the length of the principal bottom $\frac{3}{4}$ inch thick and $1\frac{1}{2}$ wide one side beaded from the centre on both sides to an edge with the upper side, they are to be nailed in the middle with 16 nails (the beaded side down $\frac{1}{2}$ of an inch apart to a piece of strong wood, as long as the box is wide 1 inch thick $1\frac{1}{2}$ wide put flat side down rounded near the ends and covered with iron to turn in the notches of the bed pieces.

At each end on the upper side, must be a piece of thin firm wood; drive the nails this way the laths and clinch them in these pieces to prevent the hands from injuring the clothes, lay the frame in the wash box, and see that all fits well and that the counter bottom plays freely up and down without either end or side touching the box on the under side, at one end must be a piece of plank, nailed on $\frac{1}{4}$ a hole bored this hole to draw off the water, — These metal bottoms are required, the bottom is the first thing to be made if the sheet be 6 feet long by 1 foot 10 inches wide, draw two straight lines $1\frac{1}{2}$ inches apart from one end to the other, allowing $2\frac{1}{2}$ inches each side to turn up, Then at one end cut along each of the lines $3\frac{1}{2}$ inches exactly of a length, now measure from the step of the cut along the lines 4 feet 8 inches, and cut the lines, cut from that measure, draw a line at an angle of 45 degrees, from the step of each cut, to the edge towards each corner, The sides and ends must be punched half an inch from the edge in a zigzag form that the rivets may not split the plank, in riveting — The sides from the cut to the regular line, must be turned up square, that the ends of the bottom when raised may come in between the sides; now turn up the sides, square with the line, where the ends of the bottom are to be riveted to the sides, the bottom parts can be punched before they are turned up & the ends of the sides punched this the holes, These metal bottoms are used as boles & sit in an arch or framework; the end that stands over the mouth of the furnace, has the metal

go to the top & that part of the side that laps round the end must be riveted to the end to strengthen the end of the bottom. There must be a square hole made at the back end of the bottom, 2 inches long by 1 inch wide to draw off the water. Then there must be a plate of metal made to fit the bottom at the turn, over the hole, and punched & the hole made & cut out to fit that in the bottom. Then a socket about 2 inches long fitted and brazed to this plate and riveted on.

Now on the back slippes the water bed is next the plank must be large inch thick & the width enough to make 8 inches from the bottom to the top of the water bed. There must be a shallow rabbit taken out of this plank, where the metal is put on & should be flagged between.

Now the border plank is to be put on, this plank is $\frac{3}{4}$ inch thick and 8 inches wide & lapped on the water bed $2\frac{1}{2}$ inches.

This plank is square ended. Now when the height of the box is known, there must be a piece of metal riveted on the top of the furnace end, and long enough to turn at each side to be riveted to the border plank, for a support to the end, instead of a clamp, the other end must have ~~no~~ clamps on it.

Where the cost of the metal bottom is thought too great a substitute can be made of almost equal value with half the cost, by having a box made as for a wooden bottom, put on a piece or two of plank at each end of the bottom, then have a sheet of iron 3 feet square punched on every edge ready for nailing; lay the sheet in the middle of the box & mark it on each side to fit the water bed, then turn up the sides and fit it to its place, & nail it to the water bed on the out sides; then fast on the plank from the ends to the metal; the piece that comes on the metal must have a shallow rabbit the thickness of the metal, then flag between them turn the box up and nail the metal to the wood inside.

She must stand out of the furnace and answer well for boilers. Let it be observed that if iron, a sheet to fast long & 2 feet wide not weighing 30 lb. is too thin for bottom & boiler.

All iron bottoms when done using must be dried & then very fast outbed over with a greasy cloth, and the wood taken out, & fast by safety. The remainder of the marking, not described with the water bottom in the box as specified with the wooden bottom, then number on writing

made according to what they are intended to perform, there is wood iron & copper bottoms smaller or larger from 10 feet 8 inches in the bottom with 2 rollers, to 9 feet or more, with 3 rollers, 2 feet in diameter or more if required.

In washing leather, wool, & other property, these large washing are worked altogether by the power of a sweep - which is the invented plan for all these washing machines to operate upon, handles are only put to them to render them portable & for immediate trial of their performance,

Instead of handles, there are hounds to couple the rollers to the sword of the sweep, these hounds should be made of rough springy wood for small machines 5 feet long 3 inches wide and 3/4 inch thick, set in suitable shape by heat with a similar iron on the lower end, as is described for the handles, a hole thro the upper end, between which the sword comes, & a pin of wood goes thro the sword and hounds, & fastened;

There must be a round put thro the hounds before the rollers to keep them in proper place, The sweep for working the machine is simple & easy made.

Have two sets 9 or 10 feet long, for a wooden bottom, one to be put on each side of the wash box, each set is let in 5 or 6 feet long, near one end of each long side, set in a foot & a half long to incline down from the top, make an open mortise an inch or more wide in each post, to receive a judgment from each end of the beam which must be as long as the posts are apart at top, this beam may be 16 inches square, with a mortise near one end, 6 inches long 1 1/2 inches wide to receive a tenon on a piece of wood as heavy as one of the rollers, this tenon must be tapering 2 feet long the longest end, cut 2 feet from the other end of the beam, make a mortise 1 1/2 inch square, at right angle with the first mortise, The square mortise is to hold a sword 2 feet long 3 inches wide & 1 1/2 inch thick of rough strong wood with several holes bored thro it near the lower end, to shorten or lengthen the arm of the rollers.

Between the sword & the end of the beam make another mortise of the same size as the one for the sword, this mortise is to be in the same square with the first, to hold a staff 6 or 7 feet long to work the sweep by.

Now set the wash box upon some plank or sides near the long end of the sets, being forward the hounds side further than the arms having a

rope fastened to the end of the staff, pull the rope which will extend the rollers & see whether the box stands at a right distance from the sword, if the rollers strike the further end, of the box move it back, if it strikes the ends move the bounds, higher up the sword, & fix something at a proper distance for the staff to counter upon,

When the sweep is fixed to boileas the ends are not wanting to go by the sides of the wash box & therefore may be shorter.

Observe that the balance weight to the beam returns the rollers freely over the clothes, if not add more weight to the end of it. The principle that induced the invention was to lighten labor & lessen friction.

Method of using the boiler. Put the water in the boiler make it as warm as for common washing by hand, then put or spread in a reasonable quantity of clothes, after soaping them sufficiently in the usual parts; now start the rollers over them, but mind to keep the fire down, so as not to boil the water till the clothes are thought fit for boiling, then raise or increase the fire, & if preferred put in lye, and boil, keeping the rollers going & when they are sufficiently boiled they will be clean & fit for rinsing. Take them out & put in more, temper the water to a right heat, lower the fire, & proceed as before until the strength of the ends is exhausted, fill the box or put in a sufficient quantity of cold water and proceed to rinse in the same manner, they were washed.

The wooden bottoms require the first pieces, then taken out & boiled in the ordinary way, in a pot or kettle & then put back under the rollers for rinsing.

By this method may be washed from the finest lace or least wear material, without friction or injury, to the coarsest cloth, sacks, & carpets.

Witness,

L. Stephens.

W. M. Tyler.
